UNITED STATES PATENT OFFICE.

HARRY JOHAN HJALMAR NATHORST, OF GELLIVARE MALMFÄLT, MALMBERGET,
SWEDEN.

ROCK-DRILL.

964,875.

Specification of Letters Patent. Patented July 19, 1910.

Application filed January 23, 1907. Serial No. 353,731.

To all whom it may concern:

Be it known that I, HARRY JOHAN HJALMAR NATHORST, a subject of the King of Sweden, and resident of Gellivare Malmfält, 5 Malmberget, Sweden, have invented new and useful Improvements in Rock-Drills, of which the following is a specification, reference being had to the drawing accompanying and forming a part hereof.

10 This invention relates to improvements in rock-drills.

The object of the invention is to decrease, as much as possible, the detrimental vibrations of such machines.

15 The invention consists chiefly in that the hammer cylinder is mounted at right angles to the compressor cylinder or cylinders and parallel to the compressor shaft so that the center lines of the hammer cylinder and the 20 compressor shaft lie in one and the same plane.

In the drawing I have shown, by way of example, a central longitudinal section of a rock-drill embodying the invention.

25 Referring to the drawing, *a* is a rotary shaft journaled in bearings *b*, *b*, and *c'* and *c''* are two cranks on the said shaft.

d' and *d''* are connecting rods, each connected to one of the cranks *c'* and *c''*. At 30 their other ends said connecting rods are connected to pistons *e'* and *e''* movable in the open cylinders *f'* and *f''* respectively. Made integral with the cover of the cylinders and extending parallel to the shaft *a* is the hammer cylinder *i*. At one end the cylinder *i* is open, and in the said end a drill-bit *m* having a shoulder *n* is inserted. At the other end the cylinder is provided with a bottom having an accurately centered hole. 40 Through the passages *h'* and *h''* the cylinder *i* communicates with the cylinders *f'* and *f''* respectively.

k is the piston working in the cylinder *i*, said piston being here constructed as a hammer and provided with a narrower cylindrical part *l* fitting exactly in the said hole in the bottom of the cylinder *i*.

50 *o* are holes in the cylinders *f'* and *f''*, said holes being so located that a communication with the open air is established, only when the pistons *e'* and *e''* are in the outermost position of their strokes.

The mode of operation of the machine is the same as in other similar machines. The

hammer is reciprocated by compression alternately at one or the other side thereof so that the hammer is caused to strike the neck of the drill-bit. On account of the narrower part of the hammer entering the hole in the bottom of the cylinder at the end 60 of the return stroke, an air cushion is formed preventing the hammer from striking the said bottom. Through the holes *o* losses by leakage are compensated for at each stroke.

65 By using a loose hammer the advantage is gained that the machine always works with the same load and always synchronous with the compressor, by which the machine as well as the motor is spared.

70 By placing the hammer cylinder at right angles to the compressor cylinder and parallel to the crank shaft the advantage is gained that the vibrations caused by the recoil in the rock-drill and those caused by the motion of the cranks and pistons do not co-operate in their action upon the shaft and its bearings. By using two compressor cylinders mounted as shown in the drawing 75 space is gained for the journaling necessary on account of the great number of revolutions and the great strains.

75 It is obvious that the hammer cylinder may be placed elsewhere than at the cover of the compressor pistons, provided the hammer cylinder be mounted at right angles to the compressor cylinders and parallel to their crank-shaft.

Having now described my invention what I claim as new and desire to secure by Letters Patent is:

1. In a rock-drill, the combination of a rotary crank-shaft, a compressor having cylinders extending at right angles to the said crank-shaft, compressor pistons driven by the said crank-shaft, a hammer cylinder built together with the compressor, said hammer cylinder being mounted at right angles to the compressor cylinders and parallel to the rotary crank-shaft, and a hammer working 100 in the hammer cylinder synchronously with the said compressor, substantially as and for the purpose set forth.

2. In a rock-drill, the combination of a rotary crank-shaft, a compressor having cylinders extending at right angles to the said crank-shaft, compressor pistons driven by the said crank-shaft, a hammer cylinder 105

built together with the compressor and communicating constantly with the compressor cylinders, said hammer cylinder being mounted at right angles to the compressor cylinders and parallel to the rotary crank-shaft, and a hammer working in the hammer cylinder synchronously with the said compressor, the length of stroke of the said hammer being greater than that of the compressor pistons, whereas the area of the

former is less than that of the latter, substantially as and for the purpose set forth.

In testimony whereof I have signed my name to this specification in the presence of two subscribing witnesses.

HARRY JOHAN HJALMAR NATHORST.
